CHARLES L. BRINK, OF LANSING, MICHIGAN.

STOP MECHANISM.

1,131,671.

Specification of Letters Patent. Patented Mar. 16, 1915.

Application filed September 23, 1912. Serial No. 721,928.

To all whom it may concern:

Be it known that I, CHARLES L. BRINK, a citizen of the United States, residing at Lansing, in the county of Ingham and State 5 of Michigan, have invented a new and useful Improvement in Stop Mechanism, of which the following is a specification.

My invention relates to bending machines and other similar devices, in which it is 10 necessary to raise and lower a certain part of the machine through a fixed range of motion, and its purpose is to make a device that shall automatically perform the said operation and shall also be under complete 15 control of the operator of the machine.

I attain these purposes by the means shown in the accompanying drawings, in which—

Figure 1 is an elevation of my device taken 20 from the front showing the operating clutch unlocked, which is its normal position except when in process of raising and lowering the form, as will be more fully explained hereafter. Fig. 2 is an elevation taken from the 25 right hand side, a part of the frame being removed to show the construction. Fig. 3 is an elevation of a part of the bender frame and form to show the connection of the device to the bender. Fig. 4 is a detail view 30 illustrating a modified way of connecting the forming member with the operating mechanism.

Referring more particularly to the drawings, 1 is the main frame of a bender and 2 the form intended to be raised and lowered by my device. For the purposes of illustration I have chosen a machine of a well known type, but it is evident that my device might be applied to any form of bender, 35 having a form adapted to be raised and lowered through a fixed distance or indeed to many other devices without departing from my invention, the only thing to be changed being the method of connecting the 40 device to the part to be moved.

3 is the main frame of my device, which as shown, is attached to one side of the bender frame, but which might be secured in any desired position without departing 45 from my invention. A shaft 4 is adapted to revolve in bearings 5 formed in the frame 50 3. A ratchet 6 is firmly secured to the shaft 4. This ratchet, however, it is unnecessary to provide with teeth except for a 55 part of its circumference, since it always occupies substantially the same position at

the termination of a stroke, and its purpose will be more fully explained farther on. A pulley 7 and pinion 8 are mounted on a sleeve adapted to revolve freely on the shaft 60 4. This pinion drives a gear 9 also mounted on a sleeve carrying a clutch 10 and adapted to revolve freely on a shaft 11, which revolves in bearings 12, formed in the frame. The opposite half, 13, of the clutch is adapted 65 to slide on the shaft 11, but compelled to revolve with it by a feather key or other similar device.

A spring 14 tends to force the jaws 10 and 13 of the clutch into engagement with 70 each other, but they are normally retained out of engagement by a pin 15 operated by a foot lever 16, links 17 and 18 and bell crank lever 19. Manifestly any other suitable form of linkage might be employed 75 according to the relative positions of gear and form. A cam 20 is formed in a sleeve 21, which is connected to the clutch jaw 13 and is preferably integrally formed with it. This cam 20 abuts against the pin 15, which 80 is normally kept pressed inward by a spring 22 so, as already stated, to prevent the members of the clutch engaging with each other. When, however, the pin 15 is drawn back by means of the foot lever 16, the sleeve 21 and 85 jaw 13 are pushed forward and engage with the jaw 10 of the clutch so that the shaft 11 makes one revolution on its axis. When this revolution is completed the pin 15, which is immediately released after pressure, 90 engages with the inclined face 23 of the cam 20 and forces the sleeve and jaw back and out of engagement.

In order to prevent the shaft 11 from making more than a single revolution when 95 released, a pin 34 is inserted between the sleeve 21 and the jaw 13 of the clutch, so as to engage with the pin 15 when a single revolution of the shaft is completed.

A pinion 24 is mounted on the shaft 11 and a 100 gear 25 having a two to one ratio to the pinion 24, is mounted on the shaft 4. The ratio between the pinion and gear being in this instance one to two, one revolution of the shaft 11 will drive the gear 25 through half 105 a revolution. The pinion and gear are so placed with relation to each other that when the gear 25 stops the pin 26 will stand substantially either in the position shown in Figs. 2 and 3 or one diametrically opposite 110 to it, that is, so that the link 27, which connects the pin 26 to the bell crank lever 28,

will be nearly on a center. Any other cycle might be obtained by a proper ratio of gears. The other extremity of the bell crank lever 28 is connected by a link 29 to a cam lever 30, which operates on the form 2 to force it downward. When the cam 30 is released, the form 2 is raised by a spring 31. If, however, only a slight degree of pressure is required, the cam 30 might be dispensed with and the form 2 raised and lowered directly by the link 29 as shown in Fig. 4. The ratchet 6 is so positioned on the shaft 4 with reference to the pin 26, that when the form 2 is pressed downward to its lowest point the teeth of the ratchet will be engaged by the dog 33 and the ratchet will thus be prevented from rebounding and revolving backward and thus releasing the pressure.

20 The operation of my device is evident from what has been already said in describing the construction. The pulley 7 being continuously driven from any suitable source of power, one pressure of the foot lever will cause the jaws of the clutch to engage and raise the form for the insertion of a new piece to be bent. A second motion of the foot lever will again cause the jaws to engage and the gear 25 will make another one-half revolution drawing the form 2 down against the article to be bent and retaining it there until released by another semi-revolution of the gear.

35 I claim as my invention and desire to secure by Letters Patent:

1. In a device of the class described, the combination of a shaft mounted for rotation, a clutch comprising a member adapted to revolve independently of the shaft, and a second member slidably mounted on the shaft for rotation therewith, said second clutch member being provided with a cam at one side thereof and with a portion extending transversely thereof, means for transmitting motion to the first mentioned member of the clutch, means for bringing the clutch members into engagement with each other, a pin movable into and out of engagement with the movable clutch member, said pin being adapted to coöperate with the cam to move the sliding clutch member out of engagement with the other clutch member, said pin being also adapted to engage the said transverse portion of the movable clutch member to limit the rotary movement of the shaft.

2. In a device of the class described, the combination of a shaft mounted for rotation, a gear fixed on the shaft for rotation therewith, and provided with a crank pin, a drive pulley and pinion connected together and sleeved for rotation on said shaft, a ratchet mechanism associated with said shaft to prevent rotation thereof in one

direction, a second shaft arranged parallel with the first shaft, a pinion fixed on said shaft and engaging with said first mentioned gear and having a predetermined ratio thereto, a clutch on the second shaft, one member of the clutch being loosely mounted on the shaft and having a pinion connected thereto and in engagement with the pinion of the first shaft, the other member of the clutch being feathered on the shaft, means operatively connected with the crank pin to transmit reciprocatory motion, means for bringing said clutch members into engagement, and means acting automatically for disengaging said clutch members after a single revolution.

3. In combination, a gear having a crank pin mounted thereon; a pinion engaging with said gear and having a predetermined ratio thereto; a clutch having one member revolvably mounted on the shaft of said pinion and the second slidably mounted on the said shaft so as to revolve therewith; means for transmitting motion to the first member of said clutch; a mechanically operated pin acting on the second member of said clutch to prevent engagement of said members; a spring acting on said second member tending to force it into engagement with said first member, and automatically operated means comprising a cam mounted on said second member and adapted to engage with said pin, so as to separate said clutch members after a single revolution, and a second pin adapted to engage with said mechanically operated pin to stop the revolution of said pinion shaft after one revolution.

4. In combination, a gear having a crank pin mounted thereon; a pinion engaging with said gear and having a predetermined ratio thereto; a clutch having one member revolvably mounted on the shaft of said pinion and the second slidably mounted on the said shaft so as to revolve therewith; means for transmitting motion to the revoluble member of said clutch; a mechanically operated pin acting on the second member of said clutch to prevent engagement of said members; a spring acting on said second member tending to force it into engagement with said first member; automatically operated means comprising a cam mounted on said second member and adapted to engage with said pin, so as to separate said clutch members after a single revolution; a second pin adapted to engage with said mechanically operated pin to stop the revolution of said pinion shaft after one revolution, and a ratchet wheel and dog in operative relation to said first mentioned gear and adapted to prevent a reversed motion thereof.

5. In combination, a gear having a crank pin mounted thereon; a pinion engaging

with said gear and having a predetermined ratio thereto; a clutch having one member revolvably mounted on the shaft of said pinion and the second slidably mounted on 5 the said shaft so as to revolve therewith; means for transmitting motion to the first member of said clutch; a mechanically operated pin acting on the slideable member of said clutch to prevent engagement of said 10 members; a spring acting on said second member tending to force it into engagement with said first member; automatically operated means comprising a cam mounted on said second member and adapted to engage 15 with said pin, so as to separate said clutch members after a single revolution; a second pin adapted to engage with said mechanically operated pin to stop the revolution of said pinion shaft after one revolution; a ratchet wheel and dog in operative relation 20 to said first mentioned gear and adapted to prevent a reversed motion thereof, and means operatively connected to said crank pin adapted to transmit reciprocating motion.
